G. C. BROWN

ELECTRIC METERING DEVICE

Filed May 22, 1922

INVENTOR:

George Carlton Brown

BY Allen Allen

ATTORNEYS.

UNITED STATES PATENT OFFICE.

GEORGE CARLTON BROWN, OF CINCINNATI, OHIO, ASSIGNOR TO GENERAL ELECTRIC COMPANY, A CORPORATION OF NEW YORK.

ELECTRIC METERING DEVICE.

Application filed May 22, 1922. Serial No. 562,631.

To all whom it may concern:

Be it known that I, GEORGE CARLTON BROWN, a citizen of the United States, and a resident of Cincinnati, in the county of 5 Hamilton and State of Ohio, have invented certain new and useful Improvements in Electric Metering Devices, of which the following is a full, clear, and exact description, reference being had to the accompanying 10 drawings, forming part of this specification.

My invention relates to electric metering devices and more particularly to those which combine a movable element operated from 15 the electric current used by the consumer and a time element which accomplishes a resetting of the movable element at definite intervals.

Such meters are used to indicate maximum 20 demand of the consumer, and in the usual form of meter the movable member operates on a friction arrow or the like, which stays wherever it is moved. Thus if a movable arrow is swung through an arc 25 and returned every fifteen minutes during a metering interval, the friction arrow will swing over its arc, and at the end of the interval will show by its position the greatest movement of the movable member for 30 any fifteen minute interval of a month.

The difficulty with such maximum demand meters is that they depend upon the timing device remaining in operation as long as the electric meter is in operation. 35 If the clock should run down or stop and more than a fifteen-minute interval be permitted to lapse prior to a resetting, then the friction arrow indication would be worthless.

It is the object of my invention to provide a combined electrically operated member and a time resetting device so interlocked or arranged that the electrically operated member will stop moving when the time device 45 stops. In a device constructed according to my invention, the reading of maximum demand at the end of an interval between meter examinations will be proper even if the time device has stopped during the 50 elapsed time. The maximum demand reading will be for a less period than the time between examinations, but so far as it goes, it will give actual maximum demand for the period that the meter was running.

There are a number of different kinds of 55 meters, to all of which my invention with mechanical alterations could be applied. In my specification I have selected for indication one accepted form of demand meter, which is merely one of a large number and 60 should be taken as such.

I accomplish my objects by that certain construction and arrangement of parts to be hereinafter more specifically pointed out and 65 claimed.

In the drawings, the figure is a partially 70 diagrammatic, isometric perspective view of a device constructed according to my invention.

Referring to the drawing, the electro- 75 magnet 1 is arranged so as to attract an armature 2. The current source for the electro-magnet is applied through conductors 3 and 4, with the conductor 4 separated from the conductor 4^a to complete the circuit by a gap 5, which is closed by the 75 operation of a rotary energy meter-driven member 6. This method of energizing the electro-magnet is not original with me.

The armature carries a pawl 7, which 80 engages in the teeth of a ratchet 8, thereby rotating it step by step as the armature is attracted and released. On the arbor 9 of the ratchet 8 is located a pinion 10 held 85 slidably but non-rotatably on the arbor. A grooved collar 11 is fastened to this pinion by means of which it is moved along on the arbor into and out of mesh.

The pinion 10 drives the gear 12, which 90 in turn drives the gear 13 by means of a small pinion 14. The gear 13 is on an arbor 14^a, which is spring-held by a spring 15, which, as the arbor turns, is placed under tension. On the upper end of this arbor 95 is a finger 16, which moves with it, this finger imparting motion to a friction arrow 17. The arrow 17 moving over the dial 18 gives the maximum demand indication desired. When the slideable pinion 10 is moved upwardly on its arbor, the mesh with the gear 12 is dis-established, so that the spring 100 on the arbor 14^a can return the finger 16 to its starting position.

This sliding action is imparted by means 105 of a forked lever 20 engaging in the groove of the pinion collar. The lever is arranged to engage the base of a disk 21, this disk having a cam face 22, which moves the free

end of the lever down at the desired interval, thereby permitting a return of the finger 16.

An arbor 23 is shown, which is driven by any desired timing device. A clock, constant speed motor, or other means may be employed for this purpose. From the arbor by a train 24, 25, 26, and 27, the arbor 28 of the disk 21 is caused to rotate.

10 By a train 29, 30, 31, and 32, an arbor 33 is caused to rotate. The arbor and the disk rotate at a speed determined by the designer of the apparatus. A usual interval for the disk 21 is once every fifteen minutes.

15 The armature of the electro-magnet carries a rod 34 on which is a stiff finger 35 having a hooked end, which moves adjacent the periphery of a ratchet 36 on the arbor 33. Thus every time the electric energy driven armature is operated, the hooked end of the finger moves into position behind one of the teeth on the ratchet. The ratchet turns counter-clockwise and unless the timing mechanism is operated, it will hold the hooked finger fast. Thus whenever the armature moves to actuate the registering device, the hook comes into engagement with the ratchet, and is released by the clock revolving the ratchet and letting the hook slip off the tooth with which it is in engagement.

20 The demand metering device is thus so arranged that when the time resetting mechanism stops, the electrically operated meter portions may continue to move but will not transmit any motion to the registering devices.

25 There are, as has been stated, different forms of meters which use time devices, and my invention is applicable to any kind of a meter using a time device and an electrically operated device.

30 Having thus described my invention, what I claim as new and desire to secure by Letters Patent, is:—

35 1. In combination with a registering device, electric-driven means for operating the registering device, a time device co-operative therewith to act upon the registering device, and means adapted to inhibit the driving connection between the electric-driven means and the registering device upon a stopping of the time device.

40 2. In combination, a registering device, electric driven means for operating said device, a time device co-operative with the electric means in operating on the registering device, means for momentarily preventing the operation of the registering device

45 by said electric driven means after each operation thereof, and means dependent upon the continuous operation of said time device for rendering said preventive means inactive.

50 3. In combination, a registering device, means for intermittently operating said registering device, a time device co-operative with said means in operating on the registering device and locking means, the release of which is dependent upon the continuous operation of the time device, for momentarily preventing the operation of said registering device by said intermittently operating means after each operation thereof.

55 4. In combination with a registering device, electric-driven means for operating the registering device, a time device co-operative therewith to act upon the registering device, and means adapted to inhibit the driving connection between the electric-driven means and the registering device upon a stopping of the time device, said means comprising a member moving continuously under influence of the time device, and a latch adapted to engage said member and be released thereby as the member moves, said latch member being adapted to hold the electrical-driven means out of operation.

60 5. In combination with a registering device, electric-driven means for operating the registering device, a time device co-operative therewith to act upon the registering device, and means adapted to inhibit the driving connection between the electric-driven means and the registering device upon a stopping of the time device, a ratchet under control of the time device, a hooked finger on the electric-driven means, said finger adapted to engage the ratchet and to be released by the ratchet as it moves, said finger being secured to the electric-driven device.

65 6. A maximum demand meter comprising a friction arrow, and a moving member to actuate it, means for resetting the moving member, electro-magnetic means having an armature actuating the moving member, said resetting means comprising a time device, a toothed member revolved by the time device, a hooked finger on the armature adapted to engage the toothed member upon each armature operation, said toothed member being moved in a direction to release the hook, as and for the purpose described.

GEORGE CARLTON BROWN.
